UNITED STATES PATENT OFFICE.

FRANK H. HEITGER, OF INDIANAPOLIS, INDIANA.

CARBURETER.

No. 900,098.

Specification of Letters Patent.

Patented Oct. 6, 1908.

Application filed April 14, 1905. Serial No. 255,586.

To all whom it may concern:

Be it known that I, FRANK H. HEITGER, a citizen of the United States, residing at Indianapolis, in the county of Marion and State of Indiana, have invented certain new and useful Improvements in Carbureters, of which the following is a specification.

My invention relates to improvements in apparatus for carbureting air with hydro-carbon vapor or gas and has special reference to improvements in carbureters of the class used for supplying carbureted air to gas or gasoline engines.

In the operation of carbureters for the production of carbureted air for gas engines, difficulty is experienced in securing and maintaining substantial uniformity of carburetion, for the reason that an engine operating at different speeds produces a varying vacuum in the carbureter and thereby tends to change the proportions of air and hydro-carbon liquid therein.

The object of my invention is to overcome the difficulties commonly experienced with carbureters, by providing a carbureter of such construction that the composition of the mixture produced therein shall be substantially constant at all speeds of the engine.

A further object of the invention is to provide a carbureter of great simplicity and minimum cost.

Other objects of the invention will appear hereinafter.

My invention is embodied, primarily, in a carbureter which comprises a mixing chamber having an air inlet at its bottom and a mixture outlet at its top, in combination with a valve for automatically controlling the admission of air at said inlet, said valve being arranged to open inwardly, a spring resisting such movement of the valve, means for adjusting said spring, a suitable reservoir, a liquid nozzle connected therewith and rising through said valve to a point above the same.

More specifically defined my invention consists in a carbureter which comprises a vertical mixing chamber having an air inlet at its bottom and a mixture outlet at its top, in combination with a valve for automatically controlling the admission of air at said inlet said valve being arranged to open inwardly, a spring resisting such movement of the valve, means for adjusting said spring, the upper part of said valve being or forming a vapor tube, and a suitably supplied

fuel nozzle rising within the valve, to a point above the same and opening within the tubular part of said valve; and further, my invention consists in a carbureter of the foregoing construction, having a rotary throttle valve in its upper part, combined with the means for adjusting said spring; and further, the invention consists in various details of construction and in combination of parts all as hereinafter described and particularly pointed out in the claims.

The invention will be more readily understood by reference to the accompanying drawings, forming a part of this specification, and in which

Figure 1 is a vertical section of a carbureter embodying my invention; and Fig. 2 is a plan view thereof.

Referring to the drawings, 10 and 19 are two liquid reservoirs one larger than the other. These reservoirs are preferably made in the same casting, and are connected by an integral duct, 18. The top of the reservoir, 10, is capped, and said reservoir contains a float, 13, for operating a liquid supply valve, 12, in the reservoir duct, 11. The reservoir cap contains an opening to guide the valve stem and serving also to admit air above the liquid. Likewise the reservoir, 19 contains a plug, 20, provided with an air opening, 21. Rising from the liquid duct, 18, at a point midway between the centers of the reservoirs is a liquid nozzle, 22. The nozzle, as shown, is threaded in the top of the duct, 18, and may be removed therefrom without disturbing any other part of the carbureter. This nozzle extends somewhat above the normal level of the liquid in the reservoir. Obviously the column height in the nozzle is kept constant by the action of the float valve, except when said column is raised by atmospheric pressure in the reservoirs. My purpose in placing the nozzle midway of the centers of the communicating columns of liquid in the two reservoirs is to prevent material variation in the height of the liquid in the nozzle when the carbureter is tilted or inclined, as frequently occurs when same is used on an automobile. The mixing chamber portion of my carbureter is preferably an integral part of the metal casting as here represented. The bottom of this portion is some distance above the duct, 18, and its top rises to a point considerably above the reservoirs. The mixing chamber, 14, is concentric with the nozzle, 22. It is

enlarged at the bottom and contains an air inlet opening, 15. This opening is occupied by a valve, 23, which operates to restrict the flow of air through said opening, 15, and thereby retain a portion of the vacuum in the chamber, 14, when the latter is placed under suction from the engine. The upper part of the valve, 23, is of reduced diameter and is hollow, forming a vapor tube, 23', concentric with the nozzle and somewhat higher. The upper end of the tube contains a number of openings so that a portion of the air may pass through the tube. The upper end of the chamber, 14, is closed by a cap or plug, 28; beneath this in the side of the chamber is a mixture outlet, 16, communicating with the pipe, 17, which leads to the inlet valve of the engine (not shown). For throttling the outlet, 16, I employ a sleeve-like throttle valve, 25, fitting the upper part of the mixing chamber, 14 and provided with an opening, 26, corresponding to the outlet opening. The sleeve has a central stem, 27, which extends through the top or cap, 28, and to this I attach a lever, 29 for turning the throttle valve to regulate the throttle opening.

31 is a spring which presses upon the upper end of the air valve, and 30 is a threaded follower arranged in the stem, 27, of the throttle valve, and fastened by a locking nut 33. The resistance of the valve, 23, to the entrance of air, may be accurately adjusted by means of the follower, 30. As shown in the drawings, the valve has an upright stem, 32, formed on or attached to the top of the vapor tube, 23', and slidable in the follower, 30, the valve being thereby held centrally over the inlet opening. During the operation of the engine and at each suction stroke thereof, air rushes into the mixing chamber, the valve, 23, being elevated in proportion to the vacuum in the chamber, 14. As explained, part of the air passes upward within the valve around the liquid nozzle, 22, vaporizing and carrying off the liquid drawn from the latter. It will be observed that the vapor thus formed within the tube, 23', passes into the mixing chamber, 14, in the form of a large number of small streams or jets, in which form it most readily admixes with the main currents of air from the lower part of the mixing chamber. As explained, the air valve is capable of any desired adjustment by means of the spring and follower, hence a mixture of any desired quality may be secured; and as the air valve proportions the admission of air to the vacuum in the chamber and to the movement of air past the nozzle, it follows that once the valve is adjusted, the composition of the mixture will remain constant, notwithstanding the varying demands of the engine for greater or less volumes of said mixture.

As various modifications of my invention 65 will readily suggest themselves to one skilled

in the art, I do not confine the same to the specific constructions herein shown and described.

Having thus described my invention, I claim as new and desire to secure by Letters Patent:

1. In a device of the class described, a mixing chamber having an air inlet at its bottom and a mixture outlet at its top, in combination with a valve in said chamber 75 and seated about the inlet opening therein, for automatically controlling the admission of air at said inlet, a spring resisting the movement of the valve, means for adjusting said spring, a vapor tube formed on said 80 valve, a nozzle of less diameter than said tube and rising therein to a point above said valve, and a suitable reservoir wherewith said nozzle is connected, substantially as described.

2. In a device of the class described, two connected reservoirs, in combination with a supply duct, a suitable float valve, a nozzle supplied from said reservoirs and rising between the same at a point midway of their 90 centers, and a mixing chamber arranged between said reservoirs to receive liquid from said nozzle, said chamber having suitable inlet and outlet openings, substantially as described.

3. In a device of the class described, a mixing chamber having an air inlet opening in its bottom and provided with a mixture outlet in its side, in combination with a rotary throttle provided in the upper part of 100 said chamber, an air valve arranged at the said inlet opening and vertically movable, a vapor tube formed on said valve and opening into said chamber, a suitable nozzle within said tube, an adjustable follower in 105 the top of said throttle valve, and a spring interposed between said follower and said air valve, substantially as described.

4. In a device of the class described, a mixing chamber, having an air inlet in its 110 bottom and an outlet in its side, in combination with a rotary throttle in the upper part of said chamber and operable from the top of said chamber, a combined air valve and mixing vapor tube in the lower part of said chamber, said tube being superimposed on said valve, a valve spring, a spring follower adjustable in the top of said throttle, a valve stem guided by and slidable in said follower, and a suitable liquid nozzle of less 120 diameter than said tube and rising to a point above said valve, substantially as described.

5. In a device of the class described, a mixing chamber having an inlet at its bottom and an outlet at its top, in combination 125 with an air valve for closing said inlet, a vapor tube rising from said air valve and containing a plurality of vapor perforations, means for adjusting the action of said valve and a liquid nozzle rising through said valve 130

and tube to a point adjacent to the perforations in the latter, substantially as described.

6. In a device of the class described, a mixing chamber having an inlet at its bottom and an outlet at its top, in combination with an air valve for closing said inlet, a vapor tube rising from said air valve, a screw plug threaded through the top of said chamber, a spring interposed between said plug and said vapor tube, and a stem on said vapor tube extending through said plug; substantially as described.

7. In a device of the class described, a mixing chamber having an inlet at its bottom and an outlet at its top, in combination

with a fluid nozzle extending into said chamber, a relatively movable vapor tube arranged concentrically about said nozzle, and a valve formed upon the bottom of said vapor tube, and adapted to close said inlet 20 opening; substantially as described.

In witness whereof, I, have hereunto set my hand and seal at Indianapolis, Indiana, this 4th day of April, A. D. one thousand nine hundred and five.

FRANK H. HEITGER. [L. S.]
